BUTANE CARBURETION

James F. Armstrong, Detroit, Mich., and James T. W. Moseley, Clayton, Mo., assignors to Carter Carburetor Corporation, St. Louis, Mo., a corporation of Delaware

Application December 23, 1946, Serial No. 717,932

10 Claims. (CL. 48—180)

1

This invention relates to fuel feed apparatus for internal combustion engines and consists particularly in a novel regulator, heater, and carburetor apparatus for supplying to the engine a normally gaseous fuel, such as butane, which is stored in a tank under relatively high pressure.

As the supply of stored gas, usually in a liquid condition, is depleted, the delivery pressure decreases and it is the function of the regulator to insure the delivery of fuel to the carburetor at a uniform, usable pressure notwithstanding. Where the engine operates at variable speeds and under variable loads, as is the case with an automotive engine, a simple pressure reducing valve will not do the work because of the decreasing delivery pressure as well as the widely varying pressures in the carburetor itself, particularly, where the main fuel nozzle is located anterior to the throttle, as is customary. Moreover, the expansion of the gases as they pass the reducing valve of the regulator results in cooling which may cause recondensation of a portion of the gases and it is necessary to overcome such recondensation.

Accordingly, it is an object of the present invention to provide a novel regulator and carburetor apparatus of the above-mentioned type of service which is constructed to supply the right proportions of fuel and air under all conditions of operation.

It is another object to provide such an apparatus with effective means for increasing the supply of fuel for starting.

It is another object to provide such an apparatus in which a volume of fuel under slight super-atmospheric pressure is maintained in immediate proximity to the carburetor nozzle during idling so that this volume of fuel is available for supply to the carburetor upon acceleration even before the regulator can readjust itself.

It is another object to provide a carburetor of the above type having a starting adjustment which is universal to the extent that the positioning of the carburetor may be widely varied in use without the necessity of reconstructing any part thereof.

These objects and other more detailed objects hereafter appearing are attained by the apparatus illustrated in the accompanying drawings in which

Fig. 1 is a perspective view of an automotive engine having the novel fuel supply apparatus applied thereto.

Fig. 2 is an enlarged side view of the carburetor.

Fig. 3 is a diagrammatic view of the apparatus

2 illustrating the manner of connecting the various parts.

Fig. 4 is a view of the carburetor looking at the opposite side from Fig. 2.

5 Fig. 5 is a top view of the carburetor, a portion being broken away substantially on line 5—5 of Fig. 7 for clearer illustration.

Fig. 6 is a vertical central section through the carburetor taken substantially on line 6—6 of 10 Fig. 5.

Fig. 7 is an elevation viewed substantially from line 7—7 of Fig. 5 with a portion removed for clearer illustration.

Figure 1 shows an internal combustion engine 15 12 of the automotive type mounted between the dash panel 13 and the usual cooling radiator 14, the latter being connected to the engine water chamber by piping 15 and 16. The cooling fan

17 is mounted on a shaft 18 extending from the water pump housing 19. A tank 20 is conveniently mounted for storing normally gaseous fuel, such as butane, under such relatively high pressure as to be initially in a liquid condition.

25 Safety valve 21 of the type illustrated in a pending application, Serial No. 734,433, filed March 13, 1947, in the names of James T. W. Moseley and James F. Armstrong, is mounted on the dash and interposed in feed line 22 from tank 20. Line 22 connects with the regulator generally indicated at 23, also mounted on the dash.

30 Carburetor 24 is mounted on intake manifold 25, both the carburetor and manifold forming part of the induction conduit system of the engine. The carburetor is of the downdraft type, but may be arranged for updraft or side draft operation.

35 Hot water lines 26 and 27 extend from the regulator to the engine water jacket and a gas feed line 28 connects the regulator and carburetor. A suction line 29 and an atmospheric vent line 30 also connect the regulator and carburetor.

40 The carburetor, as more clearly illustrated in Figs. 2, 4, 5, 6, and 7 is of the downdraft type having an upper air inlet portion 35, a central Venturi tube 36, and an outlet portion 37, flanged as at 38 for attachment to the intake manifold.

45 A butterfly throttle 39 mounted on shaft 40 controls the delivery of mixture through the engine. One or more slots 41 formed in the throat of Venturi tube 36 connects an annular space 42 around the Venturi tube with the anterior of the carburetor and constitute fuel supply nozzles. A cup-shaped casing structure 51 on the right side of the carburetor barrel (Fig. 6) has generally

50 tubular extension 52 forming a fuel ante-chamber 53. This chamber is connected to annular pas-

sage 42 through a calibrated orifice member 54 formed in the side of the carburetor barrel and variably restricted by a tapered metering valve 55. Valve 55 has a threaded stem 55a carried by a lever 56 rigid on a shaft 57 journalled in a tubular boss 58 and extending through the wall of casing 51 (Fig. 7). Lever 56 has an upward extension 59 with a lateral pin 60 received in a slot 61 formed by the folded over extremity 62 of a strap 63. This strap at its outer end is connected to a diaphragm 64 received between a shoulder 65 on casing extension 52 and a small cap 66. This diaphragm is constantly urged to the left by a coiled spring 67 and its maximum rightward movement is limited by a screw 68. Chamber 69 formed by cap 66 and the diaphragm is connected to suction port 70 posterior to throttle 39 by means of passages 71 and 72 (Figs. 2 and 7). Fuel ante-chamber 53 is provided with an inlet connection boss 73 and a by-pass 74 controlled by adjusting screw 75 which provides for supplying idling fuel to the carburetor mixture conduit posterior to the throttle. This idling bypass may be eliminated, as will be explained hereafter, in which case idling fuel would be supplied through main fuel orifice 54 and nozzles 41.

Projecting into the inlet end of the carburetor barrel is an air tube 76 which connects with an elongated boss 77 on the outside of the carburetor barrel and having a threaded opening for connection to air vent tube 38 previously mentioned. Projecting from casing 51 opposite boss 77 is a second boss 80 having a threaded opening 81 for connection to suction line 29, previously mentioned. A passage 82 (Fig. 5) extends centrally and horizontally through the boss 80 and is provided with a metering restriction 83 controlled by a needle valve 84. Valve 84 has a stem 85 projecting oppositely of tapped opening 81 in boss 80 and provided with a collar 86 between which and the adjacent end of the boss there is depressed a coiled spring 87 which constantly tends to move the needle valve out of orifice restriction 83. Connecting with passage 82 to the left of restriction 83 (Fig. 5) there is an inclined passage 88 which connects with the carburetor barrel at port 80. Also extending from passage 82 on the right hand side of restriction 83 (Fig. 5) is a cross passage 89 connecting by means of passage 90 and orifice restriction 93 with a vertical passage 94 which joins suction passage 72 previously mentioned opening into the carburetor posterior to the throttle. Passage 94 is plugged at its upper end. The passages 71, 72, and 94 constitute a Y-shaped suction passage provided with an atmospheric bleed through passages 83 and 82, the bleed being controlled by needle valve 84.

For operating needle valve 84, there is provided a lever 96 (Fig. 2) with a squared lower extremity 97 pivotally mounted on the outside of the carburetor body by a screw 98. On the upper end of lever 96 there is loosely swiveled a small block 99a having a hole 99b and screw 99c for attachment of Bowden wire cable 100 (Figs. 1 and 3). A curved lever 101 is pivoted to the carburetor body by means of a screw 102 and has parallel threaded ears 103 receiving adjusting screw 104 which bears against the squared lower extremity 97 of lever 96. At the upper end of lever 101 there is an extension 105 which rests against the extremity of needle valve stem 85. Thus, pivoting of lever 96 in either direction urges the needle valve 84 toward its seating in orifice 83 and has the effect of re-

ducing the amount of air bled into suction passages 91, 92, 94, and 72.

Opposite curved lever 101 there is provided a second, similarly shaped lever 108 pivoted to the carburetor body by means of a screw 109 and provided with threaded ears 110 receiving adjusting screw 111 which bears against the squared lower extremity of lever 96 opposite screw 104. Lever 108 has a downwardly projecting finger 112 which abuts a lug 113 formed on an arm 114 rigid with the throttle shaft. The arrangement is such that upon rotation of lever 96, the throttle valve is moved to a slightly open position for starting. Lever 114 on the throttle shaft is provided with a finger 115 which engages a rib 116 on the throttle body to limit the wide open position of the throttle. A second projection 117 on lever 114 receives adjusting screw 118 for controlling the closed or normal idling position of the throttle valve. Lever 114 forms one arm of the U-shaped throttle lever secured to the throttle shaft by a screw 119. The other arm 120 of the throttle lever is provided with an aperture 121 for connection to the usual accelerator mechanism extending into the driver's compartment.

Curved, pivoted levers 101 and 108 are yieldingly connected at their upper extremities by a coiled tension spring 122 which causes screws 104 and 111 to bear against the cam forming lower extremity 97 of lever 96. In the vertical position of lever 96, as shown in Fig. 2, needle valve 84 is withdrawn to its maximum extent from its controlled orifice 83 and the throttle valve is permitted to reach its normal idling position which is determined by engagement of rib 113 by screw 118.

Shaft 57, previously mentioned as rigidly mounting lever 56 and main orifice valve 55, extends beyond the cup-shaped casing 51 on the side of the carburetor opposite to lever 96 (Fig. 4), and rigidly mounts a curved lever 125 and loosely mounts a second lever 126. Lever 126 is connected by a link 127 to an arm 128 rigid with the throttle shaft opposite to control lever 114, 120, etc. Tight arm 125 at its extremity receives adjusting screw 129 which bears against a pad 130 on loose lever 126. By means of this arrangement, closing of the throttle valve urges shaft 57 in the counter-clockwise direction with relation to Fig. 4, or in the clockwise direction with relation to Fig. 6, so as to move valve 55 toward its most restricting position. Opening of the throttle yieldingly operates lever 125 and shaft 57 in the opposite direction through a torsion spring 131 received about the end of shaft 51. This yielding operation permits closing of valve 55, to a greater extent than is justified by the throttle position, under the influence of suction operated diaphragm 64 to provide an economizing effect during part throttle operation.

The regulator, as shown diagrammatically in Fig. 3, is formed principally of a cylindrical casing 135 with a web 136 extending thereacross. To the left of this web there is a separately formed web structure 137 which is nested within and cooperates with the casing side wall and web 136 to form a water chamber to which hot water from the vehicle cooling system is conducted by hoses 26 and 27 (Fig. 1) connected to fittings 138 and 139 (Fig. 3). Cap structure 140 closes the left-hand end of the casing and a flexible diaphragm 141 is secured between web structure 137 and this cap structure. The diaphragm is constantly urged toward the left by means of coiled spring 142 seating against web 137. A

pipe coil 143 is received between webs 136 and 137 with one of its ends connected to low pressure gas outlet 149 through a radial orifice forming a seat for a valve 172. The other end of the coil opens into first reduction chamber 153.

An inlet coupling structure on cap 149 is controlled by a high pressure inlet valve 154 operatively connected to diaphragm 141 by means of a lever 155 pivoted at 156 to the cap structure and with its upper extremity bearing against an S-shaped spring 157 projecting from diaphragm 141. The arrangement is such that gas passing inlet valve 154 may enter first reduction chamber 153 to exert its pressure on diaphragm 141. When this pressure overcomes spring 142, the diaphragm is urged to the right and valve 154 is closed. High pressure gas from chamber 153 then enters heating coil 143.

A second body structure 165 is attached to the right hand end of casing 135 and secures in position a diaphragm 166. A central opening 167 in this body structure is closed by a flexible diaphragm 168.

A cap element 169 closes the right hand side of body structure 133 and secures in position a third operating diaphragm 170. A radial opening 171 in the main casing provides for exposing the left hand side of diaphragm 166 and chamber 153 to the fuel pressure discharged past valve 172. This valve is operated by angular lever 174 pivoted at 183 on the casing.

Lever 174 has an arm 185 which, at its lower extremity bears against a piece 186 at the center of diaphragm 166. This leverage arrangement is such that the low pressure gas applied to the left side of diaphragm 166 tends to close valve 172. A small coil spring 190 compressed between angular lever 174 and web 136 normally urges the valve closed.

Central piece 188 on diaphragm 166 engages a similar piece 194 at the center of diaphragm 168 which, in turn, engages a central actuator button 195 secured to diaphragm 170. Chamber 196 at the right side of diaphragm 166 connects with air vent tube 38 (Fig. 1) leading to air tube 76 at the inlet end of the carburetor. This chamber is also connected by a cross passage 198 to chamber 199 at the right hand side of diaphragm 170. Both chambers 196 and 199 are substantially exposed to atmosphere as the reference pressure. Chamber 200 at the right hand side of primary diaphragm 141 is also exposed to atmosphere through vent 200a. Chamber 201 at the left hand side of diaphragm 170 connects with suction piping 29 leading to the carburetor mixture conduit posterior to the throttle. Intermediate diaphragm 168 serves merely to separate chambers 196 and 201 so that diaphragms 166 and 170 can be arranged in the compact, side by side manner shown. Diaphragm 166 may be considered as the secondary diaphragm or valve control and diaphragm 170 serves as the idling and starting valve control.

The relationship of the various chambers and passages and the operation of the apparatus is most clearly illustrated in diagrammatic Figure 3 in which the various parts are designated by the same reference numerals as used in the previously described figures. A tank of butane or other normally gaseous fuel under pressure is connected to inlet 152, so that its pressure is applied to the left hand side of diaphragm 141 and the pressure in primary chamber 153 is reduced and limited to about 4½ pounds per square inch. The fuel, in a liquid condition in tank

20, vaporizes as it enters chamber 158. This fuel is then lead through heating coil 143 to secondary, pressure reducing and limiting valve 172. Since chamber 186 at the left side of diaphragm 166 is connected to outlet passage 143 and thence by means of pipe 28 to the carburetor, operation of the engine draws gas from chamber 186 so as to reduce the pressure therein below the substantially atmospheric pressure in reference chamber 196 which results in leftward movement of diaphragm 166 and opening of secondary valve 172. Metering valve 55 constitutes a third pressure reducing and limiting valve in the system.

For starting, lever 96 is rotated by means of a rod or Bowden cable 100 so as to rotate curved lever 101 and close bleed vent valve 84 and apply the full force of manifold suction to passage 29 and chamber 201 at the left hand side of diaphragm 170. This diaphragm is thus urged leftwardly and through center screws 194 and 188 and lever 165 opens secondary valve 112 against spring 180 to supply an extra charge of fuel for starting. Operation of hand lever 96 also rotates curved lever 103 to set the throttle valve in a slightly open position for starting. The engine starting speed may be adjusted by means of screw 111 and the regulator fuel delivery pressure by screw 104 which determines the degree of closing of bleed vent orifice 83. When the engine fires and runs, starting cable 100 is released permitting opening of vent valve 84 by means of its coil spring 87.

During idling, very little suction is available through feed passage 28 which communicates with the fuel supply nozzles 41 anterior to the throttle. However, manifold suction is communicated through passages 72 and 29 to the left hand side of diaphragm 170 as in starting, to shift this diaphragm and provide sufficient fuel for idling. At this time, lever 123 connected to throttle lever 128 holds main supply valve 55 in its most restricting position. The regulator is adjusted with relation to this minimum valve opening so that during idling, a slightly superatmospheric pressure is supplied through passage 29 and fills carburetor ante-chamber 53 immediately adjacent the main supply nozzles and this pressure may be adjusted according to idling and acceleration requirements by varying the area ratio of restrictions 83 and 93. Thus, upon acceleration, when suction at the nozzle is relatively low, a volume of fuel is available to provide the extra richness necessary at this time. The minimum area of the annulus between valve 55 and orifice 84 may be adjusted by means of screw 129 (Fig. 4).

During so-called economy range operation, when the engine is operating under light load with the throttle in only partially open position, manifold suction is transmitted through passages 72 and 71 to economizer diaphragm chamber 69 so as to urge tight lever 125 through link 63 in a direction to urge valve 55 closed, torsion spring 131 flexing to permit this. During slow idle and early part throttle operation, and until diaphragm 170 has reached the limit of its stroke toward the left, the superatmospheric pressure existing in passage 28 and ante-chamber 53 is controlled by balancing of the force exerted by diaphragm 170 toward the left against the force exerted by the pressure in pipe 28 and chamber 186 which urges diaphragm 166 to the right. Metering of the fuel during this period is accomplished by the variation of the annulus formed by orifice 84 and valve 55, according to throttle

movement, and variation of pressure drops across orifice 54 produced by varying air flow through the carburetor. When idling and starting diaphragm 170 reaches the limit of its useful stroke to the left, or when insufficient manifold depression is available to exert an appreciable force on diaphragm 170 through passage 29, carburetor suction transmitted through passage 28 actuates secondary diaphragm 166 and valve 172 to supply gas at a substantially constant sub-atmospheric pressure. Obviously, reduction of the pressure within secondary chamber 186 also reduces pressure in primary chamber 158 so as to permit additional opening of valve 154 and the entry of additional quantities of fuel from the main tank.

The above apparatus, accordingly, is well adapted to supply fuel in the proper quantities with relation to the air drawn through the carburetor for operation of an automotive engine and to respond promptly and accurately to varied conditions of speed and loads applied thereto. Since primary and secondary gas valves 153 and 172 are normally closed, leakage of gas is prevented when the engine is not in operation. The various parts are arranged so as to fit compactly within the regulator and assembly is greatly facilitated and simplified.

The invention may be modified in various respects as will occur to those skilled in the art and the exclusive use of all the modifications as come within the scope of the appended claims is contemplated.

We claim:

1. A gas carbureting apparatus for an engine comprising a mixture conduit having a throttle, a supply passage for connecting said conduit anterior to said throttle to a source of normally gaseous fuel under pressure, a pressure regulator in said passage constructed and arranged to deliver fuel to said conduit inversely in accordance with pressure changes in said passage, a suction connection between said regulator and said conduit posterior to said throttle to modify the action of said regulator, an air bleed in said suction line, and a manual, remotely controlled valve for said bleed to vary the effectiveness of said connection.

2. A gas carbureting apparatus for an engine comprising a mixture conduit having a throttle, passage means for supplying normally gaseous fuel under pressure to said conduit anterior to said throttle, a pressure regulator in said passage means spaced substantially from said conduit, a control valve in said passage immediately adjacent said conduit, a pressure responsive device for actuating said control valve, a suction passage connecting said conduit posterior to said throttle to said regulator and said device for operating the same, an air bleed vent in said suction passage, and a manual, remotely operated valve controlling said vent for varying the effectiveness of said suction passage.

3. An apparatus as described in claim 2 adapted for use with an automotive vehicle and further including means extending to the driver's compartment to facilitate actuation of said valve in starting.

4. Gas carburetion apparatus comprising a mixture conduit having a fuel nozzle and a throttle, a fuel delivery passage connected to said nozzle, a first fuel supply control valve in said passage and adjusting means therefor including a pressure chamber with a movable wall oppositely exposed to a reference pressure and a fluid pressure connection to said mixture conduit, suction modulating means for said connection, stop

means for limiting closing movement of said throttle to a starting position, a remote control device for joint manual actuation of said modulating means and said stop means for starting purposes, a second fuel supply control valve in said fuel passage adjacent said nozzle, and an operative connection between said second control valve and said throttle.

5. A gas carbureting apparatus for an engine comprising a mixture conduit having a fuel nozzle and a throttle, a passage for supplying normally gaseous fuel to said nozzle, a fuel valve in the junction between said passage and said nozzle and controlling the passage of fuel through said nozzle, a device having an expansible and contractible chamber with an operating suction connection to the mixture conduit and operatively connected to said valve, an air bleed for said suction connection, a control valve in said air bleed, and an operative connection between said control valve and said throttle.

6. A gas carbureting apparatus comprising a mixture conduit having a throttle and a nozzle, a fuel supply passage for connecting said nozzle to a source of normally gaseous fuel under pressure, a valve in said passage immediately adjacent said nozzle, a pressure regulator in said passage upstream of said valve including a second valve and an expansible chamber having a movable wall operatively connected to said second valve, a fluid pressure connection between said chamber and said mixture conduit, and means for controlling said first valve including an operative connection between said first valve and said throttle, a second expansible chamber having a movable wall exposed to pressure conditions in said conduit, and an operative connection between said first valve and said second movable wall cooperating with said throttle in controlling said first valve.

7. A gas carbureting apparatus for an engine comprising a mixture conduit having a main fuel nozzle and a throttle, a source of normally gaseous fuel under pressure, a fuel passage connecting said source and said nozzle, a regulator for said passage including a first valve and a suction motor comprising a movable wall actuator operatively connected to said valve and opposing reference and control pressure chambers, one exposed to the fuel pressure in said passage and the other to a reference pressure, a second valve in said passage between said nozzle and said first valve, an operative connection between said second valve and said throttle for closing said second valve to idling position to supply only sufficient fuel for idling when said throttle is closed, and means for increasing said reference pressure when said throttle is closed so that said first valve will remain partially open during idling and thereby pass slightly more fuel than said second valve to increase the fuel pressure between said valves and insure an extra supply of fuel to said mixture conduit upon initial opening of said throttle and said second valve for acceleration, said last means comprising a suction connection between said reference pressure chamber and said mixture conduit posterior to said throttle, a third valve constituting a control for said last connection, and an operative connection between said last mentioned valve and said throttle adapted to close said last valve as said throttle is closed to thereby increase said reference chamber pressure.

8. Apparatus as described in claim 7 in which said fuel passage includes an enlarged chamber

portion for storing an extra supply of fuel for acceleration.

9. Apparatus as described in claim 7 in which said reference pressure increasing means further includes an air bleed for said suction connection, said third valve being in said air bleed and being actuated by said throttle when opened beyond the idling position for restricting said bleed to thereby increase the effectiveness of said suction connection upon said reference pressure.

10. Apparatus as described in claim 7 in which said second valve has a lost motion operative connection to said throttle and further including an expansible chamber device responsive to the pressure differential between mixture conduit suction posterior to said throttle and the pressure in said fuel passage for opening said second valve as the fuel passage pressure decreases, to the degree permitted by said throttle connection.
